(57) **CLAIM**

The ornamental design for a glassware holder, as shown and described.

DESCRIPTION

FIG. 1 is a perspective view of a glassware holder in accordance with the present design, shown with glassware received therein as part of the surrounding environment; FIG. 2 is a perspective view thereof;

FIG. 3 is a side elevation view thereof, the opposite side being identical thereto;

FIG. 4 is an end view thereof, the opposite end being identical thereto;

FIG. 5 is a top plan view thereof; and,
FIG. 6 is a bottom plan view thereof.

Any parts shown in broken lines form no part of the claimed design.
